UNITED STATES PATENT OFFICE.

ROBERT B. DYER, OF WAURIKA, OKLAHOMA.

LIGHTNING-ARRESTER.

1,251,194.

Specification of Letters Patent. Patented Dec. 25, 1917.

Application filed January 4, 1917. Serial No. 140,570.

To all whom it may concern:

Be it known that I, ROBERT B. DYER, a citizen of the United States, residing at Waurika, in the county of Jefferson and State of Oklahoma, have invented certain new and useful Improvements in Lightning Arresters; and I do declare the following to be a full, clear, and exact description of the invention, such as will enable others skilled in the art to which it appertains, to make and use the same.

This invention relates to certain new and useful improvements in lightning arresters designed more particularly for use in connection with a telephone or other delicate instrument susceptible to injury by the over-charging of its circuit.

The primary object of the invention is to provide a device of this character which is especially adapted for use in a single line wire and grounded telephone circuit, while another object of the invention is to generally improve upon devices of this character by the provision of an extremely simple, strong, durable and inexpensive construction, and one which will be efficient and reliable in operation and well adapted to the purpose for which it is designed.

With these and other objects in view, the invention resides in certain novel features of construction, and the combination and arrangement of parts as will be hereinafter fully described and claimed.

In the accompanying drawings forming part of the application, in which similar reference characters designate like parts throughout the several views:

Figure 1 is a side elevation of a lightning arrester constructed in accordance with this invention, showing it attached to the outside of the wall of a building and having a means extended into the interior of the building for operating it;

Fig. 2 is a front elevation of the lightning arrester, showing the various wires or conductors connected to the same;

Fig. 3 is a rear view of the base; and,

Figs. 4 and 5 are transverse sectional views taken on the planes indicated by the lines 4-4 and 5-5 of Fig. 2.

Referring more particularly to the drawings, the numeral 1 designates a base of porcelain or other suitable insulating material, said base being preferably of rectangular configuration and having suitable screw

holes in convenient places for receiving screws or bolts by which it is attached to a suitable support. The rear side or back of the base 1 is provided midway of its width with a comparatively deep recess or channel 2, the purpose of which will hereinafter appear.

Secured to the other side or front of the base 1 intermediate the ends and width thereof is a plate 3, from the central portion of which projects a screw 4, the latter extending through the intermediate portion of a U-shaped bracket 5. Between the ends of the arms of the bracket 5 is fulcrumed intermediate of its ends a metallic lever 6. One end of the lever 6 is forked and between the furcations 7 is secured an insulating block 8. A handle 9 or other means for operating the lever 6 is secured to the free end of the block 8, said free end extending beyond the adjacent free end of the lever 6 as clearly shown in the drawings.

Arranged in the recess or channel 2 in the back of the base is a pair of metallic bars 10, the adjacent edges of which are provided with saw teeth and separated by an interspace 11. Through the other ends of these bars 10 are extended screws 12, the free ends of which project completely through the base and through the intermediate portions of a pair of double spring contacts 13 and 14, the latter being disposed on the front of the base near the opposite ends thereof. The contacts 13 and 14 and bracket 5 are all arranged in longitudinal alinement so that the lever 6 may be brought into engagement with either one of the contacts when desired.

Connected to the contacts 13 and 14 and to the bracket 5 in any convenient manner, but preferably by means of the screws which mount such members to the base, are binding posts 15, 16 and 17 respectively. The various line and local circuit wires are to be attached to these binding posts as will be hereinafter described.

In using the device, it is preferably placed upon the outside of the building, the handle 9 being extended to the inside of the same through a suitable opening 18 in the wall 19 thereof. The local telephone wires 20 and 21 are connected to the binding posts 17 and 16, while the line wire 22 is connected to the binding post 15 of the contact 13. The ground wire 23 is connected to the binding post 16 of the contact 14. It is to

be herein noted that the device is to be used in connection with a single line wire and ground telephone circuit.

Under favorable weather conditions, the lever 6 is positioned so that its upper end engages the contact 13, and when in this position, the current will be conducted from the line wire 22 through the upper portion of the lever 6 to the bracket 5, then through the telephone wires 20 and 21 and telephone included therebetween to contact 14. From the contact 14 the current will be conducted to the ground by the wire or conductor 23. Under unfavorable weather conditions, that is, during a severe electrical storm, the lever 6 is moved in the other direction so as to disengage its upper end from the contact 13 and to engage its lower end with the contact 14. Should the line wire 22 be struck by lightning, the overcharging current instead of being conducted through the delicate wiring of the telephone, will pass from the binding post 15 through the screw 12 connected with the latter to the upper bar 10, across the interspace 11 to the lower bar 10, through the screw 12 to the lower contact 14, from whence it is conducted through the ground through the conductor 23. It will here be noted that when the lever 6 is in this position, both of the telephone wires 20 and 21 are connected with the ground, and are short circuited. This affords a better protection than otherwise. In addition to the function which the double contacts 13 and 14 have in co-operating with the lever 6 in closing the various circuits above mentioned, these contacts serve as a holding means for the lever 6 when it is swung to either of its two positions.

From the foregoing description, taken in

connection with the accompanying drawings, the construction, operation and use of the invention will be readily understood without a more extended explanation.

As various changes in form, proportion and in the minor details of construction may be resorted to without departing from the spirit of this invention, I do not wish to be limited to the construction shown and described, other than as claimed.

I claim:

A lightning arrester of the class described comprising a rectangular base composed of insulating material and having a longitudinally extending recess on the back thereof, a pair of aligned metallic bars disposed in said recess and having their adjacent ends separated by an interspace, a pair of double spring contacts disposed at the front of said base adjacent the inner ends thereof, screws extending through said bars, said base and the intermediate portions of said contacts for securing said bars and said contacts to said base, a plate secured to the front of said base mid-way of said contacts, a supporting bracket secured to said plate, a metallic lever fulcrumed intermediate of its ends to said bracket and adapted when actuated in one direction to engage one of said contacts and when actuated in the other direction to engage the other contact and operating means provided at one end of said lever.

In testimony whereof I have hereunto set my hand in the presence of two subscribing witnesses.

ROBERT B. DYER.
